UNITED STATES PATENT OFFICE.

JOHN L. MILLER, OF FORT COLLINS, COLORADO, ASSIGNOR OF ONE-FOURTH TO HATTIE A. BOSS, OF FORT COLLINS, COLORADO.

RAILROAD-SWITCH-OPERATING MECHANISM.

1,177,432.

Specification of Letters Patent. Patented Mar. 28, 1916.

Original application filed September 18, 1914, Serial No. 862,359. Divided and this application filed February 1, 1915. Serial No. 5,496.

To all whom it may concern:

Be it known that I, JOHN L. MILLER, a citizen of the United States, residing at Fort Collins, in the county of Larimer and 5 State of Colorado, have invented a new and useful Railroad-Switch-Operating Mechanism, of which the following is a specification.

The present invention relates to improvements in railroad switch operating mechanisms, the present application being a division of my application filed September 18, 1914, Serial No. 862,359, and which is issued as Patent No. 1,131,940, dated March 15, 1915. The present application is now limited to the train carried structure for operating the structure along the right of way as illustrated in the parent application, one object of the invention, being the provision of means mounted upon the railway rolling stock and manually operable for projecting a member upon either side of the rolling stock for engagement with the switch actuating mechanism disposed along 20 the track as illustrated in parent application.

A further object of the present invention, is the provision of a simplified mechanism carried by the rolling stock and manually 30 operable for disposition to engage a switch operating mechanism disposed along the right of way, the same being easily applied to railway cars as now used without discarding of the apparatus carried thereby.

With the foregoing and other objects in view which will appear as the description 35 proceeds, the invention resides in the combination and arrangement of parts and in the details of construction hereinafter described and claimed, it being understood 40 that changes in the prescribed embodiment of the invention herein disclosed can be made within the scope of what is claimed without departing from the spirit of the invention.

In the drawings, Figure 1 is a side elevation of a locomotive tender with the present mechanism for actuating the switch. Fig. 2 is a section taken on line 2--2 of Fig. 50 1. Fig. 3 is a view in elevation taken from the left as viewed in Fig. 1, dotted lines illustrating the position of the projecting switch actuating member. Fig. 4 illustrates

the application of the present invention to a passenger coach. Fig. 5 is a view in elevation showing the application of the present invention to a flat car. Fig. 6 is a bottom plan view thereof. Fig. 7 is a longitudinal sectional view through the switch operating mechanism carried by a moving 55 train. Fig. 8 is a detailed view of the member thereof. Figs. 9, 10 and 11 are detailed views of various parts of the present train carried mechanism.

Referring to the drawings, T designates 60 the tender of a locomotive, in which the bar 67 is so mounted, for reciprocation within the tubular support 68, as to be projected to either side to engage such means as is shown in the parent application for throwing the switch. Thus the bar 67, which carries in its outer end a roller 69, may be projected to assume the dotted line position, as shown in Fig. 3, this movement being to either side of the train according to the direction of travel thereof. Various mechanisms may be adapted for projecting the member 67, it preferably being supplied with a single lug 71, slideable within the slot 72 of the casing 68, said lug 71 also acting as a 65 means to prevent the rotation of the member 67 therewithin. Connected to the lug 71 are the terminals of the cables 73, which may be operated upon by the transversely swinging lever 74, as shown at the left in Figs. 1 and 70 2, or through the rotatable shaft 75 shown at the right in such figures. In either event, the cable is operated to actuate the member 67 to project it at either side of the train desired.

Where the present mechanism is adapted 75 for use upon a passenger car, as shown in Fig. 4, the hand wheel operated shaft 75 is preferable, while when the device is used in connection with flat cars, as shown in Figs. 5 and 6, the transverse shaft is mounted below the body of the car and has the ends of the cables 71' wound thereupon, one 80 terminal being wound thereupon, while the other is wound therefrom during the operation of the member 67.

Where the device is used upon a freight train, the mechanism as shown in Fig. 1 will be placed upon the tender of the engine, while that shown in Fig. 4 will be 105 placed upon the caboose at the end of the

train, and when no caboose is used, the mechanism as shown in Figs. 5 and 6 will be placed upon the flat or other freight car.

- By this construction it will be seen that the projection of the member 67 is under the control of the trainmen and can be operated from the train while in motion so that when the train is moving in the proper direction, and with the locomotive pulling the same, the fireman without leaving the locomotive can operate the shaft 75 and thus project the member 67 to throw the switch mechanism as illustrated in the parent application, the same being withdrawn after passing the same so that the train can fully pass within the siding as desired, the brakeman within the caboose or upon the last car of the train actuating the member 67 carried by such car to operate the mechanism of the switch, and thus place the switch in the opposite direction and close the siding without the necessity of the brakeman leaving the train.
- From the foregoing description, it is evident that with a device of this character the switch operating mechanism shown in the parent application may be operated without the stopping of the train, both in approaching and leaving the same, thus providing a thorough and practical device of this character and one which is composed of a few number of parts and therefore less liable to be put out of order or commission.

It is apparent that two lugs 71 may be employed where a single lug 71 is used upon the switch actuating projector bar 67, and also that the cable 72 may be a chain, or in fact any other mechanism which will properly operate the bar.

What is claimed is:

The combination with a car structure, of a switch operating mechanism carried thereby and including a transversely disposed tubular guide fixedly mounted and having a longitudinal slot, a bar mounted to slide in either direction within the tubular guide to project beyond either end of the guide, a lug outstanding from the bar and slidable within the slot, said lug coöperating with the ends of the slot to limit the outward movement of the bar, a flexible operating device secured at its ends to the lug, and extending in opposite directions therefrom, guides on which said flexible device is mounted, and means for actuating said flexible device, either end of the bar being adapted to be retracted into the tubular guide after said end has been projected therebeyond.

In testimony that I claim the foregoing as my own, I have hereto affixed my signature in the presence of two witnesses.

JOHN L. MILLER.
